[57] CLAIM

The ornamental design for a lifter for a toilet seat, as shown.

DESCRIPTION

FIG. 1 is an isometric view of a seat or lid lifter showing our new design;

FIG. 2 is a front elevational view thereof, the rear being a mirror image of the front;

FIG. 3 is a left end elevational view thereof;

FIG. 4 is a right end elevational view thereof;

FIG. 5 is a top plan view thereof; and,

FIG. 6 is a bottom plan view thereof.

FIG. 1

FIG. 3

FIG. 4

FIG. 2

FIG. 5

FIG. 6
